UNITED STATES PATENT OFFICE.

MICHAEL KING, OF FLAT RIVER, MISSOURI.

RADIATOR.

1,376,943.

Specification of Letters Patent.

Patented May 3, 1921.

Application filed March 20, 1920. Serial No. 367,391.

To all whom it may concern:

Be it known that I, MICHAEL KING, a citizen of the United States, residing at Flat River, in the county of St. Francois and 5 State of Missouri, have invented new and useful Improvements in Radiators, of which the following is a specification.

This invention relates to automobile radiators and has for its chief characteristic, 10 the provision of a radiator made up of a plurality of detachably connected units, so that any number of such units can be readily and easily associated to vary the cooling capacity of the radiator.

15 Another important object of the invention resides in the fact, that the radiator units referred to can be separated from the radiator proper, thus rendering every tube of the structure accessible for the purpose of 20 repair.

25 A further object of importance, resides in the provision of a substantially arch shaped member arranged immediately beneath the water inlet of the radiator, so that the water will be distributed over the entire area of 30 the distributing plate with which the tubes are connected.

To start off my invention I provide means whereby the discharge of water can be easily cut off from the radiator, this being intended for use in cool weather, so that when the motor is started it may be heated in quick order, after which the water from the 35 radiator is allowed to enter the water jacket.

40 Other objects and advantages will appear when the following detailed description is taken in connection with the accompanying drawings, the invention residing in the construction and the combination and arrangement of parts as claimed.

In the drawings forming part of this application like numerals of reference indicate similar parts in the several views and wherein,

45 Figure 1 is a front elevation of a radiator constructed in accordance with my invention.

Fig. 2 is a horizontal sectional view taken on line 2—2 of Fig. 1.

50 Fig. 3 is a vertical section taken on line 3—3 of Fig. 1.

Fig. 4 is a similar section taken on line 4—4 of Fig. 1.

55 Fig. 5 is a perspective view of one of the radiator units.

Referring to the drawings in detail 10 and

11 indicate respectively, the upper and the lower heads for the radiator, each being identical in their construction and in the nature of a substantially rectangular shaped 60 tank. Each head has one open side, which sides are disposed in corresponding relation. Each head is also provided with a horizontal flange provided with a horizontally disposed flange 12 projecting from all four 65 sides thereof. Interposed between the heads 10 and 11 are the radiator units clearly illustrated in Fig. 5, these units being designed to be associated in any predetermined numbers to vary the cooling capacity of the 70 radiator. The heads 10 and 11 can vary in size to accommodate any desired number of the radiator sections.

Each radiator section comprises spaced upper and lower members 14 and 15 respectively, each being in the form of a tank of rectangular formation in cross section. These members however are very narrow as compared to the width of the heads 10 and 11 respectively, also of the same length. 80 One wall 16 of each of the spaced members 14 and 15 are disposed in corresponding relation and provided with a plurality of openings 17 to receive the adjacent extremities of the radiator tubes 19. Any number 85 of radiator tubes can be employed with each unit. Carried by the tubes 19 are the usual cooling fins 20. As above stated a number of these units are adapted to be associated, to vary the cooling capacity of the radiator. 90 When associated, the adjacent parallel walls of the respective units are bolted or otherwise suitably secured together as at 21. When more than two units are used in the production of a radiator, the outermost units 95 are formed at one side and both ends with horizontal flanges 22 which are bolted or otherwise suitably secured to the flange 12 of the adjacent head. Interposed between the upper members 14 of the associated 100 units, at the head 10 of the radiator is a distributing plate 24 which is perforated as at 25 to establish communication between the head 10 and the tubes 19. The head 10 communicates with the water jacket through the 105 medium of an inlet pipe 24', while the head 11 communicates with the water jacket of the motor by means of a discharge pipe 25'. Arranged above the distributing plate 24 is a substantially arch shaped member 29 secured to the plate by means of the attaching flanges 30. The member 29 lies immediately

beneath the inlet opening of the head 10, and is perforated as at 31. By reason of its specific disposition, it is apparent that when the water is admitted into the head 10, it 5 strikes the arch shaped member 29, the latter serving to equally distribute the water over the entire area of the distributing plate 24.

By reason of the construction thus far described, it is apparent, that the water entering the radiator is not only equally distributed to each and every one of the tubes 19, but that the radiator units may be used together in different numbers to vary the cooling 15 capacity of the radiator. In addition to this fact, the units can be readily and easily separated when necessary to repair one or more of the tubes 19. When separated, access may be readily had to any one 20 of the tubes of the respective units.

Arranged within the outlet pipe 25 is a valve 33 provided with a stem 34 projecting through an opening in said pipe. Packing 35 of any suitable character surrounds the stem at its point of projection through the pipe 27 to provide a leakproof connection. A lever 36 is connected with the stem of the valve, while connected with the lever and a fixed part of the radiator is a spring 37 25 which normally holds the valve open. Leading from the lever 36 to the dash-board of the machine, or in other words in convenient reach of the operator, is a rod 38 through 30 the instrumentality of which the valve can

be closed against the tension of the spring. 35 Any suitable means may be employed for holding the valve in its closed position. Use is made of this valve in cool weather, in order that the motor may be heated in quick order. In other words, the communication 40 between the radiator and the water jacket of the motor is cut off, just prior to starting the motor, and the motor allowed to run an appreciable length of time to heat the same. After the motor has been duly heated, a rod 45 38 is released to allow the spring to function and move the valve to its normal open position.

While it is believed that from the foregoing description the nature and advantages 50 of the invention will be readily apparent, I desire to have it understood that I do not limit myself in this connection and that such changes may be resorted to when desired as fall within the scope of what is 55 claimed.

What I claim is:—

An automobile radiator comprising spaced head members, a plurality of radiator tubes establishing communication between the 60 head members, perforated distributing plate arranged between the upper head member and said tubes, and an arch shaped perforated member reposing upon the plate centrally thereof for the purpose specified. 65

In testimony whereof I affix my signature.

MICHAEL KING.
